UNITED STATES PATENT OFFICE.

JOHANNES DRAENERT, OF EILENBURG, GERMANY, ASSIGNOR TO ROBERT PARISER,
OF NEW YORK, N. Y.

TOOTHBUSH.

1,364,188.

Specification of Letters Patent.

Patented Jan. 4, 1921.

Application filed September 22, 1920. Serial No. 412,003.

To all whom it may concern:

Be it known that I, JOHANNES DRAENERT, a citizen of the German Republic, residing at Nordring 41, Eilenburg, Germany, have 5 made new and useful Improvements in Toothbrushes, of which the following is a specification, taken in connection with the accompanying drawing.

My invention relates to a new and useful 10 tooth brush. More particularly it relates to a tooth brush which has integral means to hold a dentifrice as pills of concentrated mouth wash, the pills being withdrawn as needed.

15 More particularly my invention relates to a tooth brush having a hollow handle forming a compartment or reservoir for the pills or other dentifrice.

20 My invention further relates to a tooth brush containing advertising matter located within the body of the brush and protected from water. Preferably this advertising matter is mounted within the hollow handle, the handle being preferably formed of some 25 material as for example celluloid, so that it, or a portion of it, is transparent, permitting the reading of the advertising matter.

30 My invention further relates to such a tooth brush in which advertising matter and the pills are both mounted within the handle.

35 My invention further relates to certain details of construction and combinations which will be more fully hereinafter described and pointed out in the claims.

40 In the figures, in which I have shown one embodiment of my invention, the same reference numerals refer to similar parts in the several figures.

Figure 1 is a plan view of my improved 45 tooth brush, with the cap shown in its two positions.

Fig. 2 is a side elevation partly broken away and showing advertising matter mounted in the handle.

45 Fig. 3 is a plan view similar to Fig. 1 except showing advertising matter as in Fig. 2.

50 Fig. 4 is a detail horizontal section, on an enlarged scale showing the cap with its pivoting and locking mechanism.

It is common practice to use a tooth brush with some dentifrice contained in a separate tube, bottle or box. This requires the handling of at least two articles. To a traveler

this is a particular annoyance as it requires 55 him, each time that he moves, to gather up and transport an additional article.

In my invention I so form a tooth brush that pills of concentrated mouth wash or other dentifrice, may be located directly 60 within the tooth brush, and preferably within the handle. A person, and particularly a traveler, when he packs his tooth brush made in accordance with my invention, knows that he also has his dentifrice. 65

My invention may be embodied in different forms. I have shown by way of example a tooth brush 1 having the bristles 2 and handle 3. Fig. 1. This handle 3 is formed hollow so as to make a compartment or reservoir 70 4 within which the dentifrice, as for example the pills 5, 5 of concentrated mouth wash, may be located.

On the end 6 of the handle, I mount a cap 7 by passing a screw 8 through the cap and 75 letting the screw threaded portion 9 of the screw be embedded within the end 6 of the handle. Preferably, though not necessarily, I place any suitable sealing material 10 over the head 11 of the screw. The un- 80 threaded portion 12 of the screw acts as a pivot upon which the cap 7 rocks.

The cap 7 is locked to the end 6 of the handle in any suitable manner. Preferably I provide the cap 7 with a chamber 13 with 85 in which is mounted the screw 14 having a stem 15, head 16, and a screwthreaded portion 17. The male threads 17 upon the screw 14 coöperate with the female screw threads 18 in the throat 19 of the end 6. 90

To lock the cap 7 in position, it is merely necessary to rock the cap upon the pivot 8 until the male screw threads 17 register with the female screw threads 18 in the throat 19. By then rotating the head 16 95 these male and female threads 17 and 18 are caused to coöperate and lock the cap 7 in its closed position as shown in Figs. 4 and 3, and in full lines in Fig. 1.

To fill the compartment or reservoir 4 100 with the pills 5 or other dentifrice, it is merely necessary to unscrew the screw 14 to release the male and female screw threads 17 and 18 permitting the screw to be raised into the compartment 13. As soon as the 105 end of the screw 14 is free from the throat 19 the cap 7 can be rotated upon the pivot 8 so that access may be had to the chamber 4,

through the throat 19, either to insert or withdraw the concentrated pills 5, or other dentifrice as may be desired.

These pills may be dissolved in a glass of water and used in cleaning the teeth, or one of them may be placed in the mouth of the user and be dissolved by the saliva.

Preferably though not necessarily my entire tooth brush is made of molded celluloid. This makes the handle transparent. The cap 7 and the screw 14 are also preferably made of celluloid. In fact the entire tooth brush is preferably formed of celluloid with the exception of the bristles 2 and 15 the pivot pin 8. This prevents any part rusting and insures that it will always be in a sanitary condition.

A mere glance at the handle, without opening the cap 7, will immediately disclose 20 whether or not there are any pills 5 within the handle, and whether or not their number is so reduced that the supply should be replenished.

My invention is also adapted for advertising purposes whether or not pills or other dentifrice are used.

I have shown for example in Figs. 2 and 3, a tooth brush in all respects the same as that shown in Fig. 1 except that in these 30 figures, a strip of paper or other suitable medium 20 is mounted within the chamber or reservoir 4 and contains advertising matter 21 which can be clearly read through the handle. Preferably this advertising 35 matter is displayed both on the back 21 and on the face 22 of the brush. Preferably, though not necessarily, the pills 5, 5 are also used in this form of my invention.

Any suitable means may be employed for 40 inserting the advertising matter within the handle. I may for example mold the handle of celluloid, or any other suitable material, leaving the front open so that the advertising matter may be inserted. The front can 45 then be closed with the face plate 23 preferably of celluloid. This face plate can be added by any well known means such as by using any suitable solvent as ether, or some similar material. To all intents and purposes the face plate 23 is integral with the 50 handle and cannot be distinguished from it except by close scrutiny.

Having thus described this invention in connection with illustrative embodiments 55 thereof, to the details of which I do not desire to be limited, what is claimed as new

and what is desired to secure by Letters Patent is set forth in the appended claims.

What I claim is:—

1. The combination of a celluloid tooth brush having a hollow handle in which pills of concentrated mouth wash or other dentifrice and advertising matter may be placed, a pivoted cap on the end of the handle to close the opening in the handle and a screw 65 to lock the cap in its closed position.

2. The combination of a tooth brush formed of a single rigid member having the bristles of the brush mounted on one end of said rigid member, the other end being the 70 handle of the tooth brush and formed hollow to act as a compartment or reservoir for pills of concentrated mouth wash, a cap pivoted on the end of the rigid handle and adapted to close the end of said handle, and 75 means to lock the pivoted cap in its operative position closing the end of the hollow handle.

3. The combination of a tooth brush formed of a single rigid member having the 80 bristles of the brush mounted on one end of said rigid member, the other end being the handle of the tooth brush and formed hollow to act as a compartment or reservoir for pills of concentrated mouth wash, a cap piv- 85 oted on the end of the rigid handle and adapted to close the end of said handle, and means carried by and moving with the pivoted cap to lock the pivoted cap in its operative position closing the end of the hollow 90 handle.

4. The combination of a tooth brush formed of a single rigid member having the bristles of the brush mounted on one end of said rigid member, the other end be- 95 ing the handle of the tooth brush and formed hollow to act as a compartment or reservoir for pills of concentrated mouth wash, a cap pivoted on the end of the rigid handle and adapted to close the end of said 100 handle, the end of the handle being provided with screw threads, said pivoted cap being provided with a chamber, a locking screw rotatably mounted in said chamber and adapted to co-operate with the screw threads 105 in the end of the handle, and means to prevent the disengagement of the locking screw from the pivoted cap.

JOHANNES DRAENERT.

Witnesses:

ALEXANDER PETER,
ALBERT STRICKERT.
